SHIFTING CARRIAGE FOR RAILS AND THE
LIKELouis Philippe Chicoine and Elzear Sauvē,
Vaudreuil, Quebec, Canada

Application November 25, 1935, Serial No. 51,548

3 Claims. (Cl. 105—144)

This invention relates to shifting carriages for rails and the like.

An object of the invention is to provide a simple, compact carriage which may be easily mounted upon railway rails and moved therealong to readily transport rails, timber and other articles, such as frogs, diamonds, etc.

A further object of the invention is to provide a device of this character which is generally advantageous in track maintenance and replacement, facilitating the handling of rails, eliminating the necessity for a large number of men to handle the rails and permitting the reversing and turning of rails particularly on bridges and embankments in a simple manner.

A further object of the invention is to provide a device which may be employed with facility to put in or take out expansion rails, wherein the device may form part of a ram for displacing rails.

With these and other objects in view, the invention consists essentially in a carriage formed to provide a channel for receiving rails with anti-friction elements on various sides of said channel to engage with the rail whereby said carriage may be readily mounted on and moved along the rail while being held thereon firmly. The carriage also includes a turntable element upon which rails and other devices may be mounted, said turntable element or swingable member operating to permit the swinging of said rails or devices as desired while being readily demountable, as more fully described in the following specification and illustrated in the accompanying drawings which form part of the same.

In the drawings:

Figure 1 is a fragmentary side elevation of a railroad rail in mounted position and carrying on its head two of the carriages supporting a single rail to be shifted along the track.

Figure 2 is a plan view of the carriage mounted on a rail head, the latter being shown in dotted lines.

Figure 3 is an end elevation of the carriage shown mounted on the rail head, the latter being illustrated fragmentarily in section.

Figure 4 is a transverse section taken through the carriage to illustrate its general construction, a rail head being shown in dotted lines engaging with the rollers of the carriage.

Figure 5 is a detailed fragmentary view showing one important use of the carriage which is turned upside down and mounted on a tie or the ground and supports thereabove a rail turned

upside down which is designed for use as a ram, the rail being positioned to engage with the angle plate of a rail joint to forcibly shift the rails through a ramming action.

Figure 6 is a view to illustrate a use similar to that referred to in Figure 5, the carriage supporting a single rail for use as a ram, the rail being tilted to engage with the upraised end of a mounted rail for forcibly shifting the mounted rails in a ramming action.

Figure 7 illustrates the carriage mounted upon a rail and carrying thereabove on its turntable a single rail, the latter being illustrated during a swinging operation wherein the tongs holding the rail being shifted are positioned closely adjacent to the carriage, and

Figure 8 is a side elevation of the carriage turned upside down, as in Figure 5, to illustrate the manner in which the rail head is supported by the carriage.

Referring more particularly to the drawings, A indicates the carriage as a whole which includes the main body 10 formed in any suitable manner so as to provide a main longitudinally extending channel 11 into which the head of a rail B may be introduced. According to the structure illustrated, the body 10 is formed with projecting arms 12 carrying vertically disposed rollers 13 which in this structure define the sides of the channel 11. These rollers are designed to engage with the sides of the rail head and to hold the carriage in firmly mounted position while assisting as antifriction elements in the movement of the carriage along the rail.

The rollers 13 are readily mounted on headed pins 14 projecting through suitable bores in the arms 12 and are firmly and easily secured by means of cotter pins 15 or the like which, as shown in Figure 2, project through the sides of the arms traversing suitable orifices in the pins.

The body 10 is preferably formed from cast steel and its underside is preferably recessed as at 16 and 17 to receive spaced apart horizontal rollers 18 which are mounted on the transverse shafts 19 journaled in the walls of the recess 16 which takes the form of a longitudinal channel extending longitudinally of the body above the channel 11. However, the channel 16 is not essential and the lower portion of the base might be formed merely with deep semicircular recesses 50 to house the rollers 18.

It will be noted that the horizontal rollers 18 project below the body 10 into the channel 11 and consequently this channel is bounded on three sides by anti-friction elements which 55

readily engage with the rail head, as illustrated clearly in Figure 3, and provide for the easy movement of the carriage along the rail. The major portion of the upper surface of the carriage is formed flat and the centre portion thereof is slightly raised as at 20 and recessed as at 21 to form a hemispherical bearing seat which is designed to receive the complementary bearing surface of a turntable member or swingable element 22, the latter being mounted by means of a headed pin 23 which extends through a bore in the turntable 22 and body 10 and may be secured by means of a cotter pin or the like projecting through an orifice 24 formed in the pin. The turntable member is provided with upwardly projecting flanges 25 at each end and its upper surface may be slightly curved as at 26. The turntable is designed to support rails or other articles and it will be apparent that articles mounted thereon may be readily turned or swung about with the turntable and readily tilted inasmuch as, due to the bearing surfaces and body 10 coupled with a certain amount of longitudinal play in the mounting of the pin 23, the turntable may be tilted in all directions.

To illustrate the use of the development reference may be made first of all to Figure 1, wherein a pair of carriages constructed according to the present invention are shown mounted upon one rail of a track and the turntable or swivel member of each carriage is supporting a single rail the base of which is lying on the turntable between their upstanding flanges. It will be realized that the rail is thus firmly supported and due to the plurality of antifriction elements provided on the carriages the latter can be moved very easily along the track and can be handled readily by one man. It is not necessary, however, to employ two carriages as shown to transport rails since a rail may be mounted adjacent to its middle on the turntable of one carriage and readily transported along the track.

When the rail or other object which is being transported along the track has been brought to its destination, the rail may be readily turned and swung if this is necessary since the turntable can be immediately operated by swinging an end of the rail, a more detailed reference to this operation being made hereafter.

On referring to Figures 5 and 6 it will be found that the carriage is particularly adaptable to putting in and taking out expansion rails wherein it is operated with a single rail to provide a very efficient ram. Referring to Figure 6 first of all, it will be seen that the carriage is mounted upon a rail and the turntable is supporting a single rail substantially at its midpoint, the end of the single rail being shown adjacent to a joint in the track. As is well known expansion rails have to be replaced according to the season of the year. For instance, in the fall it is necessary to take out the shorter rails which have been placed in the track to allow for expansion and to introduce the longer rails to provide for contraction during the cold weather. To do this it is necessary to shift the track or, in other words, part the rails to provide for a greater space to receive the longer rail. In Figure 6 one rail is shown slightly lifted with the edge of the head protruding slightly above the head of the adjacent rail, the angle bars at the joint having been removed. The necessary lift is arranged for by driving a spike between the base of the rail and the tie until the rail has been raised the desired amount. It is then a very simple matter to shift

the rail since by using the single rail carried by the carriage as a ram to strike against the lifted portion of the rail it is very easily shifted due to the great force provided for by the easily moving carriage and the weight of the rail carried thereby. In other words the combination of the carriage and single rail provides a very easily operated and effective device for this purpose in contradistinction to prior methods which necessitated a large number of men to hold and swing the rail used as a ram. This operation can also be effected without completely removing the angle bar as is known in railway practice.

On referring to Figure 5 it will be seen that the carriage, which is illustrated in dotted lines, is not mounted on a track but is placed upside down resting on its turntable on a tie. This leaves the vertical rollers 13 projecting upwardly and the horizontal rollers 18 exposed to provide a rolling base for the head of a rail as shown. The reversed rail is positioned at an angle to the track with its end adjacent to the angle bar of a joint. By moving the rail longitudinally, which is easily accomplished by reason of the fact that the head of the rail will slide readily over the rollers of the now stationary carriage, the head of the rail can be brought into contact with the angle plate and thus the work of rebalancing creeping rails is very easily accomplished. Moreover, this method saves damage to the rail being used as the ram. According to prior methods it has been usual for a number of men to swing a rail as a ram with its head uppermost and using a corner of the base of the rail to engage with the angle bar. This has resulted in a rounding off of the base of the rail thus in time rendering it unfit for use in a track. According to the method which is made possible by my carriage construction the head of the rail which comprises a larger mass of metal will not round off and thus rails may be employed for ramming operations in this way without there being any damage which would cause them to be discarded.

In the foregoing, therefore, it will be apparent that our carriage is most effective in various ways since it has been shown that it can be used as a moving member in a ramming operation or as a stationary member which will permit a carried rail to move freely. These constitute important uses apart from the transportation of articles along the track.

A particularly advantageous feature of our carriage is clearly illustrated in Figure 7. It will be noted that a rail mounted upon the carriage is swung at right angles to the track upon which the carriage is mounted and that the holding tongs are positioned closely adjacent to the track. This clearly illustrates that rails carried by our device may be swung around by men standing close to the track and far from the ends of the rail so that in the case of bridge operations or when working on a steep embankment no difficulty is encountered whatsoever, whereas without a device of this character it would be necessary for the several men handling the rail to move out practically to the ends of the rail in order to arrange to swing it. On embankments and narrow bridge work this is, of course, an impossibility.

Of course the construction may be employed for shifting other objects besides rails, and it is very effective in shifting timber in bridge decking and the like, it being particularly effective to handle in that it can be mounted and demounted with ease. For instance in the case of an oncoming train the device may be readily removed from

the rail whereas where it has been necessary in the past to employ a lorry car for bridge work and the like it has been imperative to have flag protection as it would be impossible to remove 5 the lorry car from the rails owing to restricted space.

Other devices, such as frogs, diamonds, and the like may also be transported readily, and if desired the turntable or swivel member can be readily removed to permit such devices to lie upon 10 the solid base.

The device is also particularly adapted for track laying devices wherein the old rails are shifted to one side and new rails put in their 15 place. The carriage can be placed on the old shifted track carrying the rail laying device and upon lifting the new rail the carriage can be shifted longitudinally on the old track to accurately position the new rail.

20 The development is also adaptable as an effective vehicle or base for rail grinding machines, being positioned under the end posts of the grinder. The horizontal rollers or other antifriction device employed will permit the turning of the 25 grinder and grinding wheel to follow the curved contour of the top of the track and thus reproduce accurately the curve as it exists on the rail even where rails are worn. The vertical roller or other antifriction device employed will hold the grinder 30 to the centre line of its work while also holding the machine securely on the rail.

It will be understood, of course, that the structure shown is the preferred form but that this development might be made in different ways. 35 For instance, it is possible to construct the device from strong channel iron and to employ anti-friction elements such as ball bearings in the side

of the channel member and in its top, whereas a similar construction might be used with rollers to produce a device having equal effect. We have not, however, illustrated a construction other than that preferred.

5 Various modifications may be made in the invention without departing from the spirit thereof or the scope of the claims and, therefore, the exact forms shown are to be taken as illustrative only and not in a limiting sense, and we desire 10 that only such limitations shall be placed thereon as are imposed by the prior art or are specifically set forth in the appended claims.

What we claim as our invention is:

1. A rail handling device comprising a carriage, a plurality of spaced apart anti-friction devices mounted adjacent both edges of one face of the carriage, extending at right angles to the plane thereof and adapted to engage the sides of the head of a standard type rail on which the device may be mounted, a plurality of further anti-friction devices extending parallel to the plane of the carriage and adapted to engage the top of a rail on which the device may be mounted, and a support freely rotatable on a vertical axis 20 25 on the face of the carriage opposite that from which the anti-friction devices extend.

2. A device as defined in claim 1, in which the anti-friction devices consist of unflanged rollers.

3. A device as defined in claim 1, in which the 30 anti-friction devices consist of unflanged rollers and the rollers extending parallel to the plane of the carriage are partly housed in recesses therein.
